REMOTE OPERATED TOGGLE ACTUATED GATE

Joseph C. Leary, Greenfield, Ind.

Application July 15, 1953, Serial No. 368,119

9 Claims. (Cl. 39—39)

The present invention relates to a gate actuating device by which a farm gate, or the like, can be both opened and closed from fairly remote positions on either side of the gate.

On most farms, it is customary to close lanes, drives and roadways by gates as much as twenty feet in length in order to prevent the escape of livestock, but which will, at the same time, permit the passage of very large trucks and wagons loaded with the usual farm material such as machinery, feeds, and the like. It is conventional practice in some localities to use a plurality of wagons in tandem when transporting hay, for instance, from the field to a storage place. When approaching a closed gate it is necessary for the operator to stop his conveyance short of the gate, walk to the gate and open it, drive his vehicle through the gate far enough to permit its closing, walk back to the gate and close it, and return to his vehicle; all requiring a considerable expenditure of time and effort.

It is, therefore, the primary object of my invention to provide a relatively simple and inexpensive mechanism, which can be easily installed on a conventional farm gate, and by which the gate can be both opened and closed from remote stations on either side of the gate. It is a further object to include, in such a mechanism, latching means for the gate by which the gate will be positively held in both its open and closed positions, such latching means being operable upon operation of the gate actuating mechanism from such remote stations.

A further object is to provide a novel form of operating station whereby a decided mechanical advantage can be had, when needed, to operate the gate actuating mechanism.

A still further object is to provide a novel form of latching means for the gate which can be operated either through operation of the gate actuating mechanism, as mentioned above, or independently of such mechanism, at the option of the user.

Still another object of the invention is to provide safety means, in conjunction with the latching means, which will prevent the accidental unlatching of the gate, especially by hogs and other livestock rooting about and nudging the gate.

Other objects will become apparent as the description proceeds.

To the accomplishment of the above and related objects, my invention may be embodied in the form illustrated in the accompanying drawings, attention being called to the fact, however, that the drawings are illustrative only, and that change may be made in the specific construction illustrated and described, so long as the scope of the appended claims is not violated.

Fig. 1 is a perspective view of a conventional gate shown in its closed position and showing my actuating device associated therewith;

Fig. 2 is a plan view of the gate in its open position showing the actuating mechanism associated therewith;

2

together with one of the operating stations located at a remote position from the gate on one side thereof;

Fig. 3 is an enlarged, fragmentary perspective view of a mounting detail of the actuating mechanism of Fig. 1;

Fig. 4 is an enlarged, fragmentary perspective view of a further detail of the mechanism of Fig. 1;

Fig. 5 is an enlarged, fragmentary perspective view showing the details of the latching means constituting a part of my invention; and

Fig. 6 is a perspective view showing one of the fixed latching plates which cooperates with the latching means shown in Fig. 5.

Referring more particularly to the drawings, and especially to Figs. 1 and 2, it will be seen that I have shown

a more or less conventional farm gate 10 hinged at 11, 11 upon a gate-post 12 for swinging movement between a closed position in cooperation with a first latch-post 13, and an open position in cooperation with a second latch-post 14. On the swinging end of gate 10 I provide 15 latching mechanism, referred to generally by the reference numeral 15, and shown most clearly in Fig. 5. Such mechanism comprises a bracket 16 providing a vertically arranged sleeve 17 in which is reciprocably received a bolt 18 projecting below and above the ends of the sleeve. A coiled spring 19 bears, at one end, against a shoulder 20 carried by bracket 16, and at the other end against a stop carried by bolt 18, here shown in the form of a cotter-pin 21. Thus, it will be seen that the pin 18 is continually urged toward its lowermost 20 or projected position.

A relatively horizontal lever 22 (see also Fig. 1) is supported intermediate its ends from gate 10 upon a horizontal pivot pin 23 substantially perpendicular to the plane of the gate. One end of lever 22 overhangs 25 the upper end of bolt 18 and a strand member 24 connects that end to said upper bolt end. Thus, by depressing the opposite end 25 of lever 22 bolt 18 is moved upwardly toward its retracted position.

Lever 22 is further provided with an arm 26 upstanding near the pivot pin 23, for a purpose later to become apparent.

From latch-post 13 is supported a latch member referred to generally by the reference numeral 27, and from latch-post 14 is supported a similar, but allochirally related, latch member referred to generally by the reference numeral 28. (See Figs. 2 and 6). Each such latch member comprises a base plate 29 inclined downwardly from its latch-post toward the gate 10, and preferably has a downturned corner 30 at its lowermost end. Near its upper end the plate is provided with a hole or socket 31 and an end wall 32. As gate 10 is swung toward either its open or closed position, the lower end of bolt 18 first strikes the downturned corner 30 of plate 29; as the gate continues to move, the bolt end rides up the inclined 35 plate 29 and, just before the bolt 18 reaches socket 31, the lower end of bolt 18 is moved entirely into the sleeve 17 and the lower end of said sleeve then engages and rides on up the plate 29 thereby supporting that end of the gate on the latch-post. When the bolt 18 reaches socket 31, the lower end thereof drops into the socket. The gate is thereby positively held in either its open or closed position, and, because of the gate end being supported by the lower end of sleeve 17 resting on plate 29, much of the strain upon the gate post 12 will thereby be relieved, and the gate itself will be protected against eventual sagging.

On farms where hogs are raised, these animals very often root about a gate and it is not uncommon that they actually lift the end of the gate opposite the gate post. Were this to occur with my latch mechanism, thus far described, the bolt end might be lifted out of socket 31 thereby unlatching the gate. I deem it highly desirable,

therefore, that safety means for preventing the unlatching of the gate in this manner, be provided. To this end, I provide, near the upper end of sleeve 17, a pair of wing members 33 and 34 projecting oppositely beyond the plane of gate 10. Near the upper end of floor plate 29, but in a plane spaced upwardly from said plate, I provide a tab 35. As the bolt 18 approaches socket 31, wing member 33 or 34 (depending on the direction of movement of the gate) will move beneath the tab 35, and the end of bolt 18 will then drop into socket 31. The end of the gate cannot then be raised to disengage bolt 18 from the socket. The bolt itself must be moved upward relative to sleeve 17 to unlatch the gate.

Where the wing members 33 and 34 are not used, the end wall 32 can be so spaced, relative to socket 31, that just as bolt 18 reaches its position in line with socket 31, sleeve 17 will strike end wall 32, thereby arresting movement of gate 10. Where such wing members are used, they may be of such length that their free end will strike end wall 32 to arrest gate movement. In either case, the gate will be stopped, not by the action of bolt 18 dropping into socket 31, but by the contact of sleeve 17 or the wing members with end wall 32. In this way no shearing force is ever applied to bolt 18.

I prefer to provide a mechanism for operating the gate, the actuation of such, first moving the bolt 18 out of socket 31, and thereafter swinging the gate toward its opposite position. To this end, I provide a toggle device referred to generally by the reference numeral 36 (Figs. 1 and 2). Between gate post 12 and latch-post 14, I provide an anchor post 37 spaced out of the line through said posts in the direction opposite gate 10. A bracket 38 (Figs. 1 and 3) is fixed to the upper rail of gate 10 at a point spaced from gate post 12 a distance substantially equal to the distance of anchor post 37 from the gate post. A pivot pin 39 is supported by bracket 38 upon a substantially vertical axis. As will be seen from an inspection of Fig. 3, bracket 38 comprises a pair of allochirally related side elements 38^a and 38^b slotted to interlock at one end and formed to embrace said upper rail and to be clamped thereto by means of a screw 38'. At their opposite ends, elements 38^a and 38^b are formed so that together they form a tubular portion 38" substantially axially parallel with the upper rail 10'. A rod 39', supporting the pin 39 at one end thereof, is inserted through this tubular portion and fixedly held therein by the clamping action of screw 38'. It will be seen that by loosening screw 38', the entire bracket 38 can be rotated about the axis of rail 10' to swing the pin 39 from its illustrated position, through an arc of 180°, to a position above the rail 10', in which pin 39 is substantially axially parallel with its illustrated position, or to any intermediate position where said bracket can be held by retightening screw 38'. The operating lever of the toggle device 36, now to be described, can thereby be adjusted for a purpose later to become apparent.

One end of each of a pair of links 40, 40 is oscillably received on pin 39. A pair of substantially vertically co-axial pivot pins 41, 41 are fixed on anchor post 37 and oscillably support one end each of a second pair of links 42, 42. A further pivot pin 43 pivotally connects the opposite ends of links 40 and 42. Because of the particular manner in which pin 39 is supported on gate 10, as described above, the pins 41, 41 can be raised somewhat above their illustrated position in order that the toggle device 36 will clear the upper fence strand, or in order to facilitate the use of barbed-wire strands (not shown) along the top of the fence.

Journalled upon pin 43 is a bell-crank member 44. When the gate is in its closed position, as illustrated in Fig. 1 (and in dotted lines in Fig. 2) the arms 45 and 46 of member 44 diverge away from pin 43 on opposite sides of links 40, 40 whereby the bell-crank member can be moved about pivot pin 43 to move the end of arm 46 to-

ward pivot pin 39, and the end of arm 45 substantially in the direction of gate-post 12.

A bracket 47 is fixed upon gate-post 12 and supports, at its lower end, a guide means, here shown in the form of a pulley 48. The bracket preferably carries an arm 49 projecting away from the gate-post in the direction opposite gate 10, and pulley 48 is preferably adjustably supported along the length of said arm.

Near the upper end of bracket 47 a lever 50 is pivotally mounted near its midpoint in a substantially vertical line for oscillation about a substantially horizontal axis 51. A strand member or cable 52 has one end fixed to the free end of arm 46 and the other end fixed to the lower end of lever 50, said cable passing over the pulley 48. Due to the particular positioning of the various elements of the device, it will be seen that a cable running directly from the end of arm 46 to pulley 48 would pass fairly close to pivot pin 43, when the gate is in its closed position; and that very slight mechanical advantage would, therefore, be realized. To overcome this disadvantage and thereby greatly increase the mechanical advantage of the mechanism, I prefer to provide a depending finger 53 at the end of arm 45, and to guide cable 52 around this finger on its way to pulley 48.

I provide a second guide means, here shown in the form of a pulley 54, supported near pivot pin 39. In the present embodiment, I have shown pulley 54 as being directly supported from that pivot pin by means of a ring 55 (Fig. 3) passing through a diametrical perforation through the pin. A cable or strand member 56 passes around pulley 54 and has one end fixed to the free end of arm 45 and the other end fixed to the free end of arm 26. In order to insure that no stress is placed on cable 56, except when required, I prefer to provide a coiled spring 57 having one end fixed near the end of arm 45 and the other end fixed near pivot pin 39, such as to the ring 55.

From the lower end of lever 50 a further strand member or cable 58 is led to an operating station, referred to generally by the reference numeral 59, located remote from gate 10; and from the upper end of said lever a further cable 60 is led to a similar, but allochirally related, operating station (not shown) on the opposite side of the gate.

Each operating station 59 comprises a lever 61 pivoted, intermediate its ends, for oscillation about a substantially vertical axis 62. The ends of the respective cables 58 and 60 are adjustably fixed near the ends of their respective levers 61 remote from the roadway, and the opposite ends of such levers project toward the roadway, as clearly shown in Fig. 2. By grasping the near end of arm 61, a person on the roadway can swing that end in the direction of the gate to actuate the operating mechanism in a manner shortly to be described. To do so, however, is somewhat difficult where the person is seated in a vehicle and for that reason, I prefer to provide optional means for so moving lever 61 which will give the user a decided mechanical advantage.

To this end, I provide an arm 63 fixed at one end to lever 61 near pivot point 62 and projecting away from said lever in the direction opposite gate 10. A short length of cable 64 is fixed near the free end of arm 63 and removably supported at the other end on the end of lever 61 nearest the roadway. Preferably, I provide a pin 65 in the said end of lever 61 and fix said last end of cable 64 to a short length of flexible tubing 66. The tubing serves as a handle for gripping cable 64 and can be telescopically slipped onto pin 65 to support the end of cable 64 in a convenient and accessible position to the roadway.

A person wishing to open the gate from the seat of a vehicle need only remove the tubing 66 and give a slight tug to swing the lever 61 about pivot 62. In so doing, lever 50 is rotated counter-clockwise, as viewed

in Fig. 1, thereby exerting a pulling force on cable 52. This, in turn, tends to first rock the bell-crank member 44 about pivot pin 43 to swing the end of arm 45 thereof away from pulley 54 against the resistance of spring 57. A pulling force is thereby exerted on cable 56 to rock lever 22 about pivot pin 23 to lift bolt 18 out of socket 31. Continued swinging of lever 50 will then move the pivotal connection 43, between links 40 and 42, toward pulley 48. Force is applied continually to so rock lever 50 until pivot pin 43 reaches its position nearest pulley 48. From there on the gate swings under its own momentum to its open position, as shown in Fig. 2, and bolt 18 drops into the socket 31 of the latch member 28 carried by latch-post 14. To close the gate, it is necessary only to repeat the pulling operation on either cable 58 or 60; the rocking of bell-crank 44 first moving bolt 18 out of socket 31 and thereafter swinging the gate toward its closed position with latch-post 13.

I claim as my invention:

1. The combination with a gate post, a first latch post spaced from said gate post, a second latch post equivalently spaced from said gate post in a direction substantially at right angles to the direction of said first latch post, and a gate hingedly supported from said gate post, of means for controlling the position of the distal end of said gate relative to said latch posts, comprising pivot means carried by said gate on a substantially vertical axis, a first link means having one end pivotally supported on said pivot means, an anchor post located between said gate post and said second latch post and offset, away from said pivot means, beyond a line joining said gate post and said second latch post, a second pivot means supported on a substantially vertical axis from said anchor post substantially at the height of said first pivot means, a second link means having one end pivotally supported on said second pivot means, a pivot pin pivotally connecting the other end of said second link means with the other end of said first link means, a bell crank lever journal mounted on said pivot pin with one arm normally projecting toward said gate post and the other arm normally inclining toward the distal end of said gate, means yieldingly resisting movement of said bell crank lever out of normal position, a lever, means supported from said gate post and supporting said lever for oscillation about an axis intermediate its ends, flexible strand means secured at one end to one arm of said lever, secured at its other end to said other arm of said bell crank lever, and, when said distal end of said gate is near said first latch post, flexed about said one arm of said bell crank lever, a latch keeper carried by said second latch post, a spring-pressed latch carried adjacent the distal end of said gate for alternative cooperation with said latch keepers, and strand means connected with said one arm of said bell crank lever and operatively connected to retract said latch upon movement of said bell crank lever against the tendency of said yieldingly resisting means.

2. The combination with a gate post, a first latch post spaced from said gate post, a second latch post equivalently spaced from said gate post in a direction substantially at right angles to the direction of said first latch post, and a gate hingedly supported from said gate post, of means for controlling the position of the distal end of said gate relative to said latch posts, comprising pivot means carried by said gate on a substantially vertical axis, a first link means having one end pivotally supported on said pivot means, an anchor post located between said gate post and said second latch post and offset, away from said pivot means, beyond a line joining said gate post and said second latch post, a second pivot means supported on a substantially vertical axis from said anchor post substantially at the height of said first pivot means, a second link means having one end pivotally supported on said second pivot means, a pivot pin pivotally connecting the other end of said second link means with the other end of said first link means, strand means operatively connected to said pivot pin, and remotely-actuable means for exerting a tensile stress on said strand means to move said pivot pin toward said gate post, whether the distal end of said gate is near said first latch post or said second latch post.

supported on said second pivot means, a pivot pin pivotally connecting the other end of said second link means with the other end of said first link means, a bell crank lever journal mounted on said pivot pin with one arm normally projecting toward said gate post and the other arm normally inclining toward the distal end of said gate, means yieldingly resisting movement of said bell crank lever out of normal position, a lever, means supported from said gate post and supporting said lever for oscillation about an axis intermediate its ends, and flexible strand means secured at one end to one arm of said lever, secured at its other end to said other arm of said bell crank lever, and, when said distal end of said gate is near said first latch post, flexed about said one arm of said bell crank lever.

3. The combination with a gate post, a first latch post spaced from said gate post, a second latch post equivalently spaced from said gate post in a direction substantially at right angles to the direction of said first latch post, and a gate hingedly supported from said gate post, of means for controlling the position of the distal end of said gate relative to said latch posts, comprising pivot means comprising a bracket clamped to said gate for adjustment relative thereto about a horizontal axis parallel with the plane of said gate, said bracket being formed to provide an offset socket on an axis substantially parallel with said first-named axis, pivot means comprising a bar adjustably received in said socket and provided with a pin portion having its axis substantially perpendicular to the axis of said socket, a first link means having one end pivotally supported on said pin portion, an anchor post located between said gate post and said second latch post and offset, away from said pivot means, beyond a line joining said gate post and said second latch post, a second pivot means supported on a substantially vertical axis from said anchor post substantially at the height of said pin portion, a second link means having one end pivotally supported on said second pivot means, a pivot pin pivotally connecting the other end of said second link means with the other end of said first link means, strand means operatively connected to said pivot pin, and remotely-actuable means for exerting a tensile stress on said strand means to move said pivot pin toward said gate post, whether the distal end of said gate is near said first latch post or said second latch post.

4. The combination with a gate post, a first latch post spaced from said gate post, a second latch post equivalently spaced from said gate post in a direction substantially at right angles to the direction of said first latch post, and a gate hingedly supported from said gate post, said gate including a substantially horizontal member of substantially cylindrical cross section, of means for controlling the position of the distal end of said gate relative to said latch posts, comprising a clamping sleeve bracket including a substantially cylindrical portion embracing said horizontal member for adjustment peripherally thereof, said bracket being formed to provide a substantially cylindrical socket offset from said first-named portion on an axis substantially parallel thereto, pivot means comprising a substantially L-shaped, cylindrical bar having its body clampingly received in said socket for adjustment about the axis of said socket, a first link means having one end pivotally supported on the toe of said bar, an anchor post located between said gate post and said second latch post and offset, away from said pivot means, beyond a line joining said gate post and said second latch post, a second pivot means supported on a substantially vertical axis from said anchor post substantially at the height of said first pivot means, a second link means having one end pivotally supported on said second pivot means, a pivot pin pivotally connecting the other end of said second link means with the other end of said first link means, strand means operatively connected to said pivot pin, and remotely-actuable means for exerting a tensile stress on said strand means to move

said pivot pin toward said gate post, whether the distal end of said gate is near said first latch post or said second latch post.

5. The combination with a gate post, a first latch post spaced from said gate post, a second latch post equivalently spaced from said gate post in a direction substantially at right angles to the direction of said first latch post, and a gate hingedly supported from said gate post, of means for controlling the position of the distal end of said gate relative to said latch posts, comprising pivot means comprising a bracket clamped to said gate for adjustment relative thereto about a horizontal axis parallel with the plane of said gate, said bracket being formed to provide an offset socket on an axis substantially parallel with said first-named axis, pivot means comprising a bar adjustably received in said socket and provided with a pin portion having its axis substantially perpendicular to the axis of said socket, a first link means having one end pivotally supported on said pin portion, an anchor post located between said gate post and said second latch post and offset, away from said pivot means, beyond a line joining said gate post and said second latch post, a second pivot means supported on a substantially vertical axis from said anchor post substantially at the height of said pin portion, a second link means having one end pivotally supported on said second pivot means, a pivot pin pivotally connecting the other end of said second link means with the other end of said first link means, a lever, means supported from said gate post and supporting said lever for oscillation about an axis intermediate its ends, strand means secured at one end to one arm of said lever and operatively connected at its other end to said pivot pin, remotely actuatable means extending in one direction from said gate post and connected to said one lever arm, and remotely actuatable means extending in the opposite direction from said gate post and connected to the other arm of said lever.

6. The combination with a gate post, a first latch post spaced from said gate post, a second latch post equivalently spaced from said gate post in a direction substantially at right angles to the direction of said first latch post, and a gate hingedly supported from said gate post, of means for controlling the position of the distal end of said gate relative to said latch posts, comprising pivot means comprising a bracket clamped to said gate for adjustment relative thereto about a horizontal axis parallel with the plane of said gate, said bracket being formed to provide an offset socket on an axis substantially parallel with said first-named axis, pivot means comprising a bar adjustably received in said socket and provided with a pin portion having its axis substantially perpendicular to the axis of said socket, a first link means having one end pivotally supported on

said pin portion, an anchor post located between said gate post and said second latch post and offset, away from said pivot means, beyond a line joining said gate post and said second latch post, a second pivot means supported on a substantially vertical axis from said anchor post substantially at the height of said pin portion, a second link means having one end pivotally supported on said second pivot means, a pivot pin pivotally connecting the other end of said second link means with the other end of said first link means, bracket means supported from said gate post and having a first portion projecting toward said anchor post and a second portion projecting away from said anchor post, strand-guiding means carried by said bracket first portion, a lever supported from said bracket second portion for oscillation about an axis intermediate its ends, flexible strand means secured at one end to one arm of said lever, passing through said strand-guiding means and operatively connected at its other end to said pivot pin, strand means connected to the same arm of said lever and extending away from said gate post to a remote operating station, and further strand means connected to the other arm of said lever and extending past said gate post to another remote operating station.

7. The device of claim 6 in which each of said operating stations comprises a lever, pivot means supporting said lever intermediate its ends for oscillation about a substantially vertical axis, the strand member approaching that station being fixed near one end of said lever, the opposite end of said lever projecting into a position accessible to a roadway guarded by said gate.

8. The device of claim 7 in which the lever at each operating station is substantially T-shaped, and a cable having one end secured to the distal end of the T-stem and having its other end removably supported from said opposite lever end.

9. The device of claim 8 including a pin supported near said opposite lever end, and a socketed element removably sleeved on said pin, said other cable end being secured to said socketed element.
